VIBRATORY ASSEMBLY FOR
GALVANOMETERS

George R. Morrow, Tulsa, Okla., assignor to Century Geophysical Corporation, a corporation of Delaware

Application February 7, 1949, Serial No. 74,940

7 Claims. (Cl. 171—95)

1

This invention relates to improvements in galvanometers such as are used in seismograph oscillograph cameras, and the like.

Galvanometers of the type which are conventionally used in seismograph cameras include a vibratory assembly which comprises a wire coil suspended between a pair of metallic filaments or ribbons and enclosed within a suitable housing. Such a vibrator assembly is designed to oscillate rotatively about its vertical axis in response to the passage of electric currents through the coil when the latter is subjected to the magnetic flux passing between opposed magnetic poles. A small mirror is ordinarily mounted on a part of the suspension and is designed to reflect a light beam onto a moving film in order to record the oscillations of the coil.

Such galvanometers are ordinarily of extremely minute dimensions and it is desirable in almost all cases to provide a construction having the maximum degree of sensitivity to the actuating energy. In order to assure maximum sensitivity and efficiency, it is highly desirable that the vibratory assembly be as nearly perfectly balanced, statically and dynamically, as possible.

In the more conventional constructions of such galvanometer assemblies, the mirror is normally mounted on the assembly by attachment to a suspension filament or to the coil and will ordinarily be disposed in a position which is displaced or off-set from the axis of oscillation of the assembly. Since the mirror, although very small, will have substantial mass, as compared with the remainder of the assembly, it will ordinarily create a condition of unbalance in the assembly which must be effectively counter-balanced, as by providing a suitable counter-balancing mass in an appropriate position on the assembly. This necessarily involves additional parts, expense and effort in construction and in adjustment of the vibratory assembly and reduces the electrical efficiency of the galvanometer, especially where electro-magnetic damping is used.

Accordingly, it is a principal object of this invention to provide an improved form of galvanometer assembly constructed to provide improved static and dynamic balance therein.

Another object is to provide a galvanometer construction in which the mirror is symmetrically disposed about the axis of oscillation of the galvanometer.

Still another object is to provide an improved suspending connection between the coil and the suspension filaments in which the mirror is en-

2

closed in alignment with the axis of oscillation of the galvanometer.

Other and more specific objects and advantages of this invention will become apparent from the following detailed description when read in conjunction with the accompanying drawings which illustrate a useful embodiment in accordance with this invention.

In the drawings:

10 Fig. 1 is a front elevational view of a galvanometer vibratory assembly in accordance with this invention;

Fig. 2 is a cross-sectional view along line 2—2 of Fig. 1;

15 Fig. 3 is a side elevational view of the structure shown in Fig. 1;

Fig. 4 is a front elevational view of the mirror supporting element adapted to connect the coil to the upper suspension element of the galvanometer;

20 Fig. 5 is a side view of the element shown in Fig. 3;

Figs. 6 and 7 are front and side elevational views of a modified connection element adapted

25 for connecting the lower suspension filament to the lower end of the coil;

Fig. 8 is a side elevational view of one of the spools on which the galvanometer coil is wound;

Fig. 9 is an end view of the spool shown in Fig. 1; and

30 Fig. 10 is a fragmentary view illustrating another embodiment of the spool shown in Figs. 7 and 8.

Referring to the drawings: The galvanometer assembly comprises an elongated coil 10 comprising a number of turns of very fine wire wound over a pair of spools, indicated generally by the numerals 11—11. A generally U-shaped connector or clevis, indicated generally by the numeral 12, connects spool 11 at the upper end of the

40 coil to an upper metallic suspension filament or ribbon 13. A mirror 14 is enclosed within the arms of clevis 12 above the coil. A second U-shaped connector or clevis 15 connects the lower spool 11 to a lower suspension filament or ribbon 16.

This assembly will ordinarily be mounted in a suitable casing (not shown) in any suitable manner, as shown, for example, in Marvin E. Morrow Patent No. 2,439,576, April 13, 1948. In such galvanometers, coil 10 will normally be suspended in a magnetic gap where it will be subject in the usual manner to magnetic flux passing therethrough.

Spools 11, (Figs. 8 and 9) will ordinarily be constructed of ivory, plastic or any other suitable 55 electrically non-conducting material, and com-

prises a cylindrical central portion 17 about which the coil is wound and having end flanges 18-18 and cylindrical trunnions 19 extending outwardly from flanges 18. The spools may be provided with an axial aperture 20. Upper connector or clevis 12 (Figs. 4 and 5) consists of a U-shaped element having elongated arms 21-21 constructed generally of a strip of electrically conducting metal. The ends of the arms are provided with eyes 22 in which trunnions 19 are adapted to be journaled. The base or curved end portion of the clevis may be provided with flanges 23-23 extending laterally from opposite edges thereof to stiffen or reinforce the connector at this point. The upper suspension filament or ribbon 13 is attached to connector 12 by looping an end of the ribbon about the base portion of the connector and soldering the loop to form a permanent connection between the filament and the connector, as illustrated particularly in Figs. 1 and 3. Mirror 14 is inserted between arms 21 of the clevis 12 and will ordinarily be of flat rectangular shape adapted to fit snugly between the arms and will ordinarily be held in place by cementing the edges of the mirror to the adjacent flat inner faces of arms 21. Lower connector 15 (Figs. 6 and 7) is likewise a U-shaped element constructed of a strip of flat electrically conducting metal having arms 25-25 provided at their ends with eyes 26 for receiving the trunnions 19 on lower spool 11. Lower suspension filament 16 will be connected to the base portion of clevis 15 in the same manner as upper filament 13 is connected to the upper connector 12, as described above. The opposite ends of coil 10 will be connected to the respective connectors 12 and 15 at 27 and 28 respectively.

As illustrated particularly in Figs. 1, 2 and 3, it will be seen that the arrangement of mirror 14 between arms 21 of the upper connector is such that its plane will lie generally in a vertical plane passing transversely through the center of the vibratory assembly and that the axis of oscillation of the assembly will pass vertically through the mirror.

By reason of this construction, it will be seen that mirror 14 will now be disposed symmetrically about the axis of oscillation of the vibratory assembly and the vibratory assembly will be substantially balanced, both statically and dynamically.

Trunnions 19 will ordinarily be made of a length, so related to the thickness of the metal strips forming the clevises, that when inserted in eyes 22 and 26, respectively, the outer ends of the trunnions will be flush with the outer faces of arms 21 and 25, respectively. This arrangement will generally permit narrowing the dimensions of the assembly as a whole, thereby permitting corresponding narrowing of the flux gap in which the coil will be installed, and thereby increasing the sensitivity of the galvanometer.

Fig. 10 illustrates another embodiment of the spool construction in which trunnions 19 are provided with inwardly tapering or under-cut peripheral surfaces 30, which will assist in holding the connectors in place on the spools, since the vibrations of the assembly would tend to urge the clevis arms along the tapering surfaces inwardly against flanges 18.

It will be understood that various changes and alterations may be made in the details of the illustrative embodiment without departing from the scope of the appended claims but within the spirit of this invention.

What I claim and desire to secure by Letters Patent is:

1. A vibratory assembly for galvanometers, comprising, a coil, a pair of suspension elements attachable to opposite ends of the coil, generally U-shaped connector members connecting the ends of said coil to said suspension elements, the ends of said coil being supported between the arms of the respective connector members, and a mirror mounted between the arms of one of said connector members and symmetrically arranged therein with respect to the longitudinal axis of said assembly.
2. A vibratory assembly for galvanometers comprising, a coil, a pair of spaced spools about which said coil is wound, said spools extending transversely of said coil, a pair of suspension elements attachable to opposite ends of said coil, connector members for connecting said suspension elements to said coil, at least one of said connector members being of generally U-shape having its base portion connected to one of said suspension elements and its arms connected to opposite ends of one of said spools, and a mirror mounted between said arms symmetrically with respect to the longitudinal axis of said assembly.
3. A vibratory assembly for galvanometers comprising, a coil, a pair of spaced spools about which said coil is wound, said spools extending transversely of said coil and having trunnion members extending laterally from the ends thereof, a pair of suspension elements attachable to opposite ends of said coil, connector members for connecting said suspension elements to said coil, at least one of said connector members being of generally U-shape having its base portion connected to one of said suspension elements and having apertures in the ends of its arms in which said trunnions are insertible, and a mirror mounted between said arms symmetrically with respect to the longitudinal axis of said assembly.
4. A vibratory assembly in accordance with claim 3 in which said one of said connector members is constructed of flat strip metal.
5. A vibratory assembly in accordance with claim 3 in which said one of said connector members is constructed of flat strip metal, the base portion of said connector member having a pair of stiffening flanges extending laterally outwardly from the opposite edges thereof.
6. A vibratory assembly in accordance with claim 3 in which said one of said connector members is constructed of flat strip metal, and said mirror is of flat generally rectangular shape having its side edges attached to the opposed flat faces of the arms of said connector members.
7. A vibratory assembly for galvanometers, comprising, a coil, a pair of suspension elements attachable to opposite ends of the coil, connector members for connecting said suspension elements to said coil, at least one of said connector members being of generally U-shape and supporting an end of the coil between the arms thereof, and a mirror mounted between said arms symmetrically with respect to the longitudinal axis of said assembly.
